GOLF PUTTER HEAD

Richard F. Warner, 28999 Gates Mills Blvd.,
Pepper Pike, Ohio 44124

Filed Feb. 7, 1972, Ser. No. 224,398

Term of patent 14 years

Int. Cl. D21—02

U.S. Cl. D34—5 GH

Fig. 1

Fig. 2

Fig. 3

Fig. 4

Fig. 5

Fig. 6

FIG. 1 is a top plan view of a golf putter head, showing my new design;

FIG. 2 is a front elevational view thereof;

FIG. 3 is a side elevational view thereof;

FIG. 4 is a rear elevational view thereof;

FIG. 5 is a bottom plan view thereof; and

FIG. 6 is an elevational view from the opposite side to FIG. 3.

I claim:

The ornamental design for a golf putter head, as shown.
